UNITED STATES PATENT OFFICE.

JACOB J. HIEBERT, OF MOUNTAIN LAKE, MINNESOTA.

WATER-HEATER.

1,158,806.

Specification of Letters Patent.

Patented Nov. 2, 1915.

Application filed February 17, 1915. Serial No. 8,848.

To all whom it may concern:

Be it known that I, JACOB J. HIEBERT, a citizen of the United States, residing at Mountain Lake, in the county of Cottonwood and State of Minnesota, have invented new and useful Improvements in Water-Heaters, of which the following is a specification.

The invention relates to heaters, and more particularly to the class of water heaters.

The primary object of the invention is the provision of a heater wherein exhaust steam is circulated through a coil which is disposed within the body of the heater so that the water contained therein will become heated from the coil and can be drained therefrom for any desired use.

Another object of the invention is the provision of a heater wherein the steam coil has associated therewith at intervals baffle plates which cause the cold water to remain passive about the coil for the heating thereof, while the hot water is precipitated throughout the extent of the coil, thereby assuring the thorough heating of the water within the heater.

A further object of the invention is the provision of a heater of this character wherein the entire construction thereof is of novel form to assure the perfect working of the same and also to allow the cleaning thereof when the occasion requires.

A still further object of the invention is the provision of a heater of this character which is simple in construction, reliable and efficient in its use, strong, durable, and inexpensive in manufacture and installation.

With these and other objects in view, the invention consists in the construction, combination and arrangement of parts as will be hereinafter fully described, illustrated in the accompanying drawings, and pointed out in the claims hereunto appended.

In the drawings: Figure 1 is a front elevation of a heater constructed in accordance with the invention. Fig. 2 is a side elevation thereof. Fig. 3 is a vertical longitudinal sectional view through the heater. Fig. 4 is a vertical transverse sectional view on the line 4—4 of Fig. 3, looking in the direction of the arrows. Fig. 5 is a horizontal transverse sectional view on the line 5—5 of Fig. 3, looking in the direction of the arrows. Fig. 6 is a sectional view on the line 6—6 of Fig. 1.

Similar reference characters indicate cor-

responding parts throughout the several views in the drawings.

Referring to the drawings in detail, the heater comprises a body or casing 10 forming a water container or receptacle supported upon legs 11, and has in its bottom a removable screw threaded plug 12 so that the same can be readily and easily drained for the cleaning of the container when the occasion requires. Located within the body or casing 10 is a sinuous coil formed from a plurality of pipe like sections 13, the meeting ends of which are provided with flanges 14 through which are passed bolt members 15 for detachably connecting the pipe sections 13 together. At the bottom of this coil and extending therefrom through one side of the body or casing 10 is an inlet pipe section 16 through which is introduced the steam to the coil, while at the opposite end of the latter and extended through the top of the body or casing 10 is the outlet pipe section 17 for delivery of steam from the said coil. The steam within the coil serves to heat the water within the body or casing 10, and this water circulates therein in a manner presently described.

Tapped or otherwise mounted to extend through the top of the body or casing 10 is a T-shaped water inlet nozzle 18 which delivers the water into the casing or body 10, while arranged interiorly of the latter contiguous to the points of the bends in the coil formed from the respective pipe sections 13 are baffle plates 19 which serve to retard the progress of the cold water by causing the backing thereof at intervals throughout the extent of the coil, while the hot water will freely flow thereover and precipitate into troughs 20 fixed interiorly of the body or casing 10 alternately at opposite sides thereof so as to be located at the bends in the steam coil for deflecting the water through feed tubes 21 mounted in the sections 13 of the coil and extending entirely through the bends therein, the water when circulating in this manner being thoroughly heated, whence it may be drawn off through the outlet 22 which is in the form of a flanged nipple 23 adapted to be detachably connected with any suitable suction pump.

Connected to and leading from the lowermost stretch of the steam coil through the bottom of the body or casing 10 is a drain pipe 24 so as to relieve condensation in the

coil. Provided in the front of the body or casing 10 are suitable doorways which are closed through the medium of door sections 25 which are detachably fastened in position for closing the doorways in any suitable manner, and on the removal of these door sections 25 access may be had to the coil of the interior of the body or casing of the heater for cleaning purposes.

10 Mounted on one side of the body or casing 10 and communicating therewith is a suitable water gage 26 for determining the quantity of water therein.

From the foregoing description, taken in connection with the accompanying drawings, the construction and manner of operation of the device will be clearly understood, and therefore a more extended explanation has been omitted.

20 What is claimed is:—

1. A water heater comprising a water container, having an inlet and outlet, a sinuous shaped steam coil arranged interiorly of the container and having opposite ends passed through the respective top and side thereof, water circulating tubes passed transversely through the coil at the points of the bights therein, troughs arranged interiorly of the container at the points of the tubes for deflecting the water therethrough.

25 2. A water heater comprising a water container, having an inlet and outlet, a sinuous shaped steam coil arranged interiorly of the container and having opposite ends passed through the respective top and side thereof, water circulating tubes passed transversely through the coil at the points of the bights therein, troughs arranged interiorly of the container at the points of the tubes for deflecting the water therethrough, and baffle plates arranged directly above the superposed stretches of the steam coil.

30 3. A water heater comprising a water container, having an inlet and outlet, a sinuous shaped steam coil arranged interiorly of the container and having opposite ends passed through the respective top and side thereof, water circulating tubes passed transversely

through the coil at the points of the bights therein, troughs arranged interiorly of the container at the points of the tubes for deflecting the water therethrough, baffle plates arranged directly above the superposed stretches of the steam coil, and a drain pipe leading from the lowermost stretch of the coil through the bottom of the container.

4. A water heater comprising a water container, having an inlet and outlet, a sinuous shaped steam coil arranged interiorly of the container and having opposite ends passed through the respective top and side thereof, water circulating tubes passed transversely through the coil at the points of the bights therein, troughs arranged interiorly of the container at the points of the tubes for deflecting the water therethrough, baffle plates arranged directly above the superposed stretches of the steam coil, a drain pipe leading from the lowermost stretch of the coil through the bottom of the container, and a plurality of superposed doors detachably mounted on the front of the container.

5. A water heater comprising a water container, having an inlet and outlet, a sinuous shaped steam coil arranged interiorly of the container and having opposite ends passed through the respective top and side thereof, water circulating tubes passed transversely through the coil at the points of the bights therein, troughs arranged interiorly of the container at the points of the tubes for deflecting the water therethrough, baffle plates arranged directly above the superposed stretches of the steam coil, a drain pipe leading from the lowermost stretch of the coil through the bottom of the container, a plurality of superposed doors detachably mounted on the front of the container, and a removable plug at the bottom of the container.

In testimony whereof I affix my signature in presence of two witnesses.

JACOB J. HIEBERT.
